UNITED STATES PATENT OFFICE

WILLIAM W. JOLLY, OF MINNEAPOLIS, MINNESOTA

DESIGN FOR A COMBINATION ASH TRAY AND PAPER WEIGHT

Application filed October 23, 1931. Serial No. 41,493. Term of patent 3½ years.

To all whom it may concern:

Be it known that I, WILLIAM W. JOLLY, a citizen of the United States, residing at Minneapolis, in the county of Hennepin and State of Minnesota, have invented a new, original, and ornamental Design for a Combination Ash Tray and Paper Weight, of which the following is a specification, reference being had to the accompanying drawing, forming a part thereof, wherein—

Fig. 1 is a perspective view of a combina-

tion ash tray and paper weight showing my new design; and

Fig. 2 is a vertical section taken substantially on the line 2—2 of Fig. 1, as indicated by the arrows.

What is claimed is:—

The original design for a combination ash tray and paper weight substantially as shown.

WILLIAM W. JOLLY.
